OIL BURNER

Filed April 3, 1926

LEWIS F. SARTORIUS INVENTOR

FIG. 4

Patented Aug. 30, 1927.

1,640,731

UNITED STATES PATENT OFFICE.

LEWIS L. SCOTT, OF ST. LOUIS, MISSOURI.

OIL BURNER.

Application filed April 3, 1926. Serial No. 99,539.

This invention relates to oil burners as used for heating homes, and is applied to a furnace that was originally designed to burn coal. The usual method of installing the oil burner in the coal furnace is to remove the grate bars and to project the burner into the ash door of the furnace. The lower part of the furnace that was formerly the ash space, is converted into a combustion chamber for the oil fire by laying a floor and side walls of fire brick.

In many instances, the inside diameter of the furnace is as small as 15", and the distance from the burner nozzle to the fire brick floor is only 3 or 4". This gives us a combustion chamber which is rather close to the fuel nozzle, with the exception of the space above, which space above is large. Under these conditions, it is very difficult to prevent the formation of carbon on the floor and walls of the combustion chamber.

I have found that by setting the fuel nozzle eccentric in the air mixing chamber so that there is more air under and on the sides of the fuel spray than on the top side of said spray, I can change the form of the flame, as compared to the "round flame burner", and thereby prevent the formation of carbon on the floor and side walls of the combustion chamber.

I am aware of the fact that the flat flame type of burner, such as shown in Patent No. 1,086,714, issued to D. J. Irish, dated February 10th, 1914, is not new. The type of burner shown in the Irish patent, however, is not adapted to the conditions I have before mentioned, because, (as I have before stated), of the space limitation on the sides, as well as on the bottom. In the Irish patent, the space conditions at the top and bottom are very limited, and there is a great deal of space on either side. My type of burner might be well called an eccentric flame burner, so as to distinguish it from the round flame burner and the flat flame burner.

In the accompanying drawings, Figure 1 is a top view of my burner assembly, shown installed in a furnace, and also showing a diagram of the electric wiring.

Figure 2 is an enlarged sectional view of my burner head.

Figure 3 is a front end view of Figure 2.

Figure 4 is a back end view of Figure 2, shown in reduced size, and with the oil dia-

phragm removed.

Referring now to the drawing, the numeral 1 indicates an electric motor which operates a blower wheel 2 and an oil pump 3. The numeral 4 is a suction pipe running from pump 3 to an oil tank, not shown. 5 60 is the discharge from pump 3, which runs to casting 6, which casting connects to fuel spray nozzle 7. The pump 3 is adapted to force liquid fuel through nozzle 7, at from 20 to 100 pounds pressure, so that fuel will 65 be sprayed into a very fine fog-like mist. 8 is an air receiver which is connected to the blower casting 9 by the air pipe 10. By referring to Figure 4, it will be seen that the air receiver 8 is in the form of an involute 70 curve and is adapted to rotate the air which rotating air will pass into the outer flame director 11. The numeral 12 is a conical tip placed on the end of the outer air director. 13 indicates a section of a furnace 75 into which the oil flame is projected. 14 indicates an inner air director which is supported by the nozzle extension 15, through the screws 16, which screws are threaded into the part 17 in a manner that permits 80 said screws to tighten against the nozzle extension 15. The numeral 18 indicates a circular disc, made of insulating material such as porcelain. The disc 18 is provided with six small air holes 19. The disc 18 is secured to the part 17 by the screws 20 and is adapted to carry the spark wires 21, which wires are secured to disc 18 by the nuts, as clearly shown in Figure 2. The wires 22 and 23 connect to the spark wires and run to 85 the insulating block 24, which block is carried by the air receiver head 25. The air receiver head 25 also carries the nozzle extension tube 15, which tube is held secure by the set screw 26. 90

I will now describe the electrical connections and control devices.

The numerals 28 and 29 indicate the main power wires. 29 runs directly to motor 1 and spark transformer 30. The wire 28 100 runs to motor 1 and spark transformer 30 through the relay switch 31. The high tension wires 32 and 33, of the transformer 30, run to the spark wires 34 and 35. The numeral 36 indicates a small transformer, 105 which is connected to power wires 28 and 29, and which reduces the 110 volt circuit to about 15 volts. The numeral 37 indicates a room thermostat, which is usually placed in the living room of the house and controls 110

the operation of the burner according to room temperature. The wire 38 runs from the transformer 36, through room thermostat 37, wire 39 and relay switch 40, and 5 back to transformer 36, thereby completing the 15 volt circuit.

When the room temperature drops so as to close the contacts on room thermostat 37, the relay switch 40 will be energized, thereby closing the switch 31 and starting the motor 1 and spark transformer 30. Fuel will be sprayed out of the nozzle 7 and air will be forced from the blower through the pipe 10 into the air receiver 8 and will be 15 caused to take a rotating motion by said air receiver, and will flow to the fuel spray through air directors 11 and 14. The electric spark, at the terminals of the spark plug, will ignite the fuel and the oil flame 20 will burn in the combustion chamber 41. It will be noted that the fuel tube 15 and fuel nozzle 7, and all parts carried thereby, are set eccentric from the air director extension 11—this is plainly shown in Figures 2 and 3. 25 By referring to Figure 3, it will be evident that the quantity of air around the fuel spray will be greatest on the bottom and least on the top. The air distributed around the sides of the spray will be almost the 30 same as if the nozzle were set concentric with the air tube 11.

I claim:

1. In an oil burning device of the class described, in combination with a spray nozzle 35 and means for supplying fuel thereto, means

for igniting the fuel, means for furnishing air to the fuel spray to promote combustion, a mixing cone for causing the air to be mixed with the fuel spray, a disc located back of the fuel nozzle in the path of the air going to the fuel spray, an air receiver which receives air from an air supply means and which causes said air to rapidly rotate, said air receiver having a projecting casting in which is enclosed said fuel nozzle, ignition means, mixing cone and disc, said fuel nozzle, ignition means, mixing cone and disc being located eccentric from the air receiver casting. 45

2. In an oil burning device of the class described, in combination with a spray nozzle and means for supplying fuel thereto, means for igniting the fuel, means for furnishing air to the fuel spray to promote combustion, a mixing cone for causing the air to be mixed with the fuel spray, a disc located back of the fuel nozzle in the path of the air going to the fuel spray, an air receiver which receives air from an air supply means and which causes said air to rapidly 50 rotate, said air receiver having a projecting casting, said casting having its outlet formed with a reduced cone-like diameter, in which is enclosed said fuel nozzle, ignition means, mixing cone and disc, said fuel nozzle, ignition means, mixing cone and disc being located eccentric from the air receiver casting. 55

In testimony whereof, I have hereunto set my hand.

LEWIS L. SCOTT.
